UNITED STATES PATENT OFFICE.

OSWALD H. HANSEN, OF PORT WASHINGTON, WISCONSIN, ASSIGNOR TO HANSEN CANNING MACHINERY CORPORATION, OF CEDARBURG, WISCONSIN, A CORPORATION OF WISCONSIN.

BEET TOPPER.

Application filed September 14, 1925. Serial No. 56,127.

- This invention relates in general to improvements in mechanisms for removing superfluous appendages and undesirable substances from objects such as tuberous vegetables, and relates more specifically to improvements in the construction and operation of machines for automatically removing leaves, roots and dirt from beets, corn or the like.
- 10 An object of the invention is to provide an improved machine for removing leaves and other undesirable material from beets or the like, which is simple in construction and efficient in operation.
- 15 Some of the more specific objects of the present improvement, are as follows:—
To provide simple, compact and efficient mechanism for automatically removing the leaves, roots and dirt from vegetable tubers such as beets, or the husks and silk from corn on the cob.
- 20 To provide an improved toppler or husker of the inclined fluted roll type, wherein the various elements are effectively adjustable to produce maximum efficiency of operation.
- 25 To provide improved means for effecting free delivery of materials from toppling or husking machines in order to enhance the capacity and to prevent clogging thereof.
- 30 To provide means for enclosing and effectively protecting the bearings and driving gearing of beet topplers or the like, against ingress of dirt, while permitting convenient access to the enclosed parts.
- 35 To provide an improved drive for toppling or husking machines, and means for effectively lubricating the driving and supporting elements.
- 40 To provide simple, efficient and readily manipulable means for effecting relative angular adjustment of the rolls of topplers or huskers, about their axes of rotation.
- 45 To provide improved means for supporting the rolls of and for adjusting the driving gearing of beet topplers or corn huskers.
- 50 To provide other improvements in the details of construction and operation of beet topping or corn husking machines, whereby the cost of construction is reduced to a minimum and the efficiency of operation is enhanced to a maximum.
- Some of the novel features of beet toppler construction, disclosed but not specifically claimed herein, form the subject matter of copending applications Serial No. 670,429, filed October 24, 1923, Serial No. 687,191, filed January 19, 1924 and Serial No. 732,875, filed August 18, 1924.
- A clear conception of embodiments of the various features of the present invention and of the operation of mechanisms constructed in accordance therewith, may be had by referring to the drawings accompanying and forming a part of this specification in which like reference characters designate the same or similar parts in the various views.
- Fig. 1 is a top view of an improved toppling or husking machine comprising four simultaneously driven cooperating fluted rolls.
- Fig. 2 is a longitudinal vertical section taken through one of the rolls of the improved toppling or husking machine.
- Fig. 3 is a part sectional rear view of the improved toppling or husking machine.
- Fig. 4 is an enlarged fragmentary sectional view through a portion of the driving mechanism of the improved toppling or husking machine.
- Fig. 5 is an enlarged transverse section through the adjusting mechanisms of two cooperating fluted rolls.
- The improved beet topping machine specifically illustrated herein as embodying the invention, comprises in general, a stationary main frame consisting of laterally spaced side frames 24 connected by a plurality of cross braces and other elements; four normally fixed parallel longitudinally inclined roll supports or shafts 7 adjustably supported in bearings 21, 22, associated with two of the connecting elements of the main frame; two pairs of parallel inclined fluted rolls 2, 3 rotatably supported upon the stationary shafts 7; a hopper consisting of inclined side plates 10, 11 and an end plate 12 for confining and guiding the bodies to be treated along the upper surfaces of the rolls 2, 3; and improved driving mechanism for continuously rotating the rolls 2, 3 about their supporting shafts 7.
- The stationary inclined roll supporting shafts 7 are supported at their lower ends in the bearings 21 formed in the lower cross frame 20, and have their upper ends supported in the bearings 22 formed in the gear housing 4 and the gear housing cover 5. Each of the supporting shafts 7 is provided

near its lower end with a thrust collar 19. The fluted rolls 2, 3 are journaled upon the shafts 7 above the thrust collars 19, the lower extremities of the rolls coacting directly with these collars. The medial portions of the rolls 2, 3 are provided with grease confining chambers and the interiors of the supporting shafts 7 are provided with ducts for insuring proper lubrication of the roll bearings. The rolls 2 have cooperating longitudinal ridges and grooves which intermesh during rotation of these rolls, and the same is true of the cooperating rolls 3. The rolls of each set are rotatable about the supporting shafts 7, in opposite directions and the lower cross frame 20 is provided with recesses 18 between the rolls of each set and beneath the discharge ends of the rolls in order to permit free delivery of materials therefrom.

The improved driving mechanism for rotating the rolls 2, 3 of each set in opposite directions about their supporting shafts 7, comprises a main transverse power shaft 15 supported below the upper ends of the shafts 7 in bearings associated with the gear housing 4, and having driving and idler pulleys 16, 17 associated with a projecting end thereof; spur gears 31 secured to the transverse shaft 15 within the housing 4; spur gears 30 rotatably supported upon stub shafts 33 which are clamped in position between the casing 4 and the cover 5, and meshing with the gears 31; bevel gears 32 drivingly connected to the spur gears 30; bevel gears 14 meshing with the bevel gears 32 and rotatably supported upon the outer roll supporting shafts 7; and intermeshing spur gears 13 drivingly associated with the rolls 2, 3 of each set. The spur and bevel gears 13, 14, 30, 31, 32 are all housed within the gear housing 4 and the cover 5, being readily accessible upon removal of the cover 5. The spur gears 13 are journaled directly upon the shafts 7 and are formed integral with coupling members 28. Each of the rolls 2, 3 has a coupling member 29 formed integral with its upper end. The coupling members 28, 29 coact with each other and are relatively angularly adjustable about the axes of their supporting shafts 7, by means of set screws 34 which are capable of being locked in position by means of locking screws 38. The coupling members 28, 29 are also connected by means of studs 35 disposed within elongated slots 36, and nuts 37 engaging the threaded stud ends. The point of penetration of the housing 4 by the power shaft 15, is packed by means of a stuffing box 26, and similar stuffing boxes 23 seal the joints between the coupling members 28 and the housing 4 and cover 5, thus providing a tightly sealed grease confining chamber 25 within the housing 4 and cover 5. The upper ends of the shafts 7 are provided with

threaded extensions or portions 9 of reduced diameter which project outwardly beyond the housing 4 and cover 5, and which are engaged by adjusting and locking nuts 27, see Fig. 4.

The side plates 10 of the confining and guiding hopper may be removably attached directly to the side frames 24 and have their upper ends connected by means of the hopper end plate 12 which is supported upon a rigid shield or plate 8 snugly embracing the upper ends of the rolls 2, 3. The shield 8 may be connected to the gear housing cover 5 by means of a guard plate 6 which protects the coupling members 28, 29 and which is conveniently removable to permit adjustment of the coupling.

During normal operation of the improved beet topper, the cooperating fluted rolls 2, 3 of each set are rotated continuously in opposite directions upon their supporting shafts 7, by means of power applied to the driving pulley 16 and transmitted from this pulley through the power shaft 15 and the gears 31, 30, 32, 14, 13 directly to the rolls 2, 3. The beets or other objects which are to be treated, are supplied in bulk to the upper end of the guiding and confining hopper and advance by gravity along and above the rolls 2, 3 between the hopper side walls 10. The individual beets are tumbled and tossed about by the rotating rolls 2, 3 until the tops and other superfluous appendages such as roots, are eventually drawn downwardly between the cooperating ridges and grooves of the rolls and are nipped from the tubers. The materials thus removed from the tubers, drop by gravity to the space between the side frames 24 and may be removed from time to time, in any convenient manner. The cleaned bulbs or tubers roll downwardly along the rotating rolls 2, 3 and are thoroughly scoured, being eventually discharged through the lower open end of the hopper.

If it is found that the ridges and grooves of the rolls 2, 3 of either set do not properly cooperate to effectively remove the superfluous appendages from the beets, the guard plate 6 may be removed and the rolls relatively angularly adjusted about their supporting shafts 7 by releasing the clamping nuts 37 and the locking screws 38 and manipulating the adjusting set screws 34, see Figs. 4 and 5. After proper relative angular adjustment of the rolls has been effected, the set screws 38 and the nuts 37 may again be returned to locking position thus retaining the rolls in adjusted position. If it is found that the bevel gears 14, 32 or that the spur gears 13 do not properly cooperate, the individual rolls 2, 3 together with their couplings and associated gearing may be shifted longitudinally of the roll axes by manipulating the locking and

adjusting nuts 27. It will thus be apparent that perfect adjustment of the various elements to produce maximum efficiency of operation is readily attainable.

- 5 The grease chamber 25 within the housing 4 and cap 5, may be filled with lubricant through fittings provided for this purpose and all bearings of the machine are conveniently accessible for lubricating purposes.
- 10 The stuffing boxes 23, 26 prevent escape of lubricant and ingress of dirt to the gearing and bearings, and the shield 8 and plate 6 effectively protect the coupling members 28, 29. The rolls 2, 3 and their supporting shafts 15 7 as well as the stub shafts 33 are quickly removable upon removal of the cover 5, guard plate 6 and shield 8 thus facilitating dismantling and assembly of the machine. The recesses 18 formed in the element 20 20 beneath and between the cooperating rolls 2, 3 effectively prevent lodging of material at the discharge ends of the rolls, and enhance free delivery of the beets and hence the capacity of the machine.
- 25 It will also be apparent that the rolls 2, 3 are all identical in structure and hence interchangeable, and the same is true of various other similar elements. By thus forming the elements of the machine, the cost 30 of construction is reduced to a minimum and the manufacturer is enabled to carry a minimum number of different parts in stock.

It should be understood that it is not desired to limit the invention to the exact details of construction and operation herein shown and described, for various modifications within the scope of the claims may occur to persons skilled in the art.

40 It is claimed and desired to secure by Letters Patent:—

1. In combination, a pair of cooperating rolls rotatable in opposite directions to remove appendages from objects traveling therealong and inclined to deliver the treated objects over the lower ends thereof, means providing supporting bearings located entirely within said rolls and shielded from contact with the objects treated, and means for effecting movement of said bearings along the roll axes.
2. In combination, a pair of cooperating rolls rotatable in opposite directions to remove appendages from objects traveling therealong and inclined to deliver the treated objects over the lower ends thereof, stationary shafts providing internal supports for said rolls, and means for effecting longitudinal adjustment of said shafts.
3. In combination, a pair of cooperating rolls rotatable in opposite directions to re-

move appendages from objects traveling therealong and inclined to deliver treated objects over the lower ends thereof, and means for effecting adjustment of said rolls 65 longitudinally of their axes.

4. In combination, a pair of cooperating rolls rotatable in opposite directions to remove appendages from objects traveling therealong and inclined to deliver treated 70 objects over the lower ends thereof, and means for effecting relative angular adjustment of said rolls about their longitudinal axes.

5. In combination, a pair of cooperating 75 rolls rotatable in opposite directions to remove appendages from objects traveling therealong and inclined to deliver treated objects over the lower ends thereof, stationary shafts providing internal supports for 80 said rolls, and means for effecting relative angular adjustment of said rolls about their supporting shafts.

6. In combination, a pair of cooperating rolls rotatable in opposite directions to 85 remove appendages from objects traveling therealong and inclined to deliver treated objects over the lower ends thereof, and a common support for said lower roll ends, said support being recessed below the roll 90 axes between said roll ends to permit unobstructed delivery of material from and between said ends.

7. In combination, a pair of cooperating 95 rolls rotatable in opposite directions to remove appendages from objects traveling therealong and inclined to deliver the treated objects over the lower ends thereof, means providing supporting bearings located entirely within said rolls and shielded from 100 contact with the objects treated, and a common support for said bearings spanning the space beneath said lower roll ends, said support being recessed below the roll axes between said roll ends to permit unobstructed 105 delivery of material from and between said ends.

8. In combination, a pair of cooperating rolls rotatable in opposite directions to remove appendages from objects traveling therealong and inclined to deliver the treated objects over the lower ends thereof, stationary 110 shafts upon which said rolls are rotatably mounted, and a common support for the lower projecting ends of said shafts, said support being recessed below the roll axes between said roll ends to permit unobstructed 115 delivery of material from and between said ends.

In testimony whereof, the signature of the 120 inventor is affixed hereto.

OSWALD H. HANSEN.
